UNITED STATES PATENT OFFICE.

EMANUEL LOEWENHERZ, OF CHICAGO, ILLINOIS.

TOOTH-CLEANING DEVICE.

1,312,334.

Specification of Letters Patent.

Patented Aug. 5, 1919.

Application filed October 1, 1915. Serial No. 53,594.

To all whom it may concern:

Be it known that I, EMANUEL LOEWENHERZ, a citizen of the Republic of Poland, residing at Chicago, in the county of Cook 5 and State of Illinois, have invented a new and useful Tooth-Cleaning Device, of which the following is a specification.

This invention relates to a tooth cleaning device.

10 An object of the invention is to provide improvements in tooth cleaning devices of that kind in which a rubbing element may be detachably inserted into the head portion of the device. The means for holding the 15 detachable rubbing element in place and for effecting readily the release of the same when it is desired to exchange the rubbing element are provided on the head portion opposite to that surface on which the holding 20 device for the rubbing element is located.

It is also an object of the invention to provide a device of this kind in which the cleaning element is adapted to retain by absorption liquids of beneficial influence for 25 the teeth, being at the same time suitable for the retention of tooth pastes or tooth powders to the same, or to a higher, extent than the cleaning devices provided with bristles. This object is attained by providing a tooth 30 cleaning device in which a soft pad, containing, for instance, cotton batting or cotton fabric, or some other similar substance capable of absorbing liquids or pastes, is used in rubbing contact with the teeth.

35 With these and other objects in view I have illustrated various embodiments of the invention in the accompanying drawing, wherein—

Figure 1 shows on an enlarged scale in section, a device of this kind adapted for the reception of two rubbing pads, one of the pads being shown inserted.

Fig. 2 is a top plan view, somewhat enlarged, of the device adapted to receive 45 three pads, the rubbing pads being not shown.

Fig. 3 is a longitudinal section through the device on line 3—3 of Fig. 2.

Fig. 4 is a perspective view of a locking element retaining the pad clamp in operative position.

Fig. 5 is a sectional view similar to Fig. 1 through a modified embodiment of the invention, also on a larger scale.

55 Similar reference characters relate to similar parts in the various figures.

The improved tooth cleaning device comprises a metal back 1 connected with a handle 2, similar to the handles of the ordinary tooth brush. The back 1 has a plurality of 60 slots 3, which are formed by punching or in some other way severing from the material of the back strips 4, leaving one longitudinal edge of the strip 4 in connection with the material of the back and bending the 65 punched strip into a plane forming an angle with the plane of the back. The free edge of the punched strip is bent sinuously so as to provide corrugations or teeth 5 to strengthen the holding power of the strip 70 on a soft pad.

A companion holding member in the form of a small angle plate having the flanges 6 and 7 is pivotally mounted by means of short extensions 9 in the material of the 75 back 1, said pivotal extensions being located in suitable eyes or bearings 10 at the ends of the slot; said bearings being formed in the embodiment illustrated by punching small strips from the metal of the back as indicated at 10', and bending the same into the form of loops. The free edge of the flange 6 is also provided with corrugations or teeth 8, which increase the holding power of this member. In supporting this companion member pivotally it is obvious that upon release of the lower flange 7 this flange will drop downwardly, so that the other flange will be swung in a direction away from the stationary strip 4, which has been 90 punched from the back.

The flange 7 of the movable holding member may be made of somewhat heavier stock than the other flange 6, so that upon release of said member the flange 7 will overbalance 95 the flange 6 and drop into release position. From the drawing it is apparent that both of the holding flanges in operative position are inclined toward each other in order to obtain a strong grip on the pad to be inserted between the same.

In order to force this companion holding member into operative position, a locking slide 11 may be inserted from the free end of the back in direction toward the handle, 105 said locking slide being guided by projecting ledges 12 on the under side of the back. This slide may be provided with a downwardly projecting flange 14, which facilitates the gripping of the same by the user 110 of the device, and the other end may be provided with an angular, downwardly pro-

jecting portion 15. The last named element will serve for automatically lifting the flanges 7 of all of the movable holding members when the slide is inserted.

- 5 The insertion or removal of the slide 11 through the space limited between the flanges 7 and the ledges 12 may be effected in spite of the depending angular portion 15, as said angular portion is somewhat narrower than 10 the slide itself, shoulder 16 being formed between the body of the slide and the depending portion.

The device is used in the following way:

After withdrawing the locking slide 11 15 and permitting thereby the holding device formed by the two flanges 4 and 6 to open by gravity, the user inserts a pad 30 between the flanges 4 and 6 of each holding device. He then returns the slide 11 into locking position. The slide forces the flange 7 against the under surface of the back 1, the lifting movement being initiated by the depending flange 15 of the slide. The cleaning device is then ready for use, and after use the rubbing 25 pads 30 may readily be removed through withdrawal of the slide, and the device can be thoroughly cleansed. Upon withdrawal of the slide the flange 7 of the movable holding member will by gravity drop into releasing position. The insertion of the locking member will automatically restore said movable holding member into closing position.

The elements will be held clearly in locking position, owing to the elasticity of the material of which they are made, and owing to the fact that the movable flange 6 presses against the pad of cotton inserted between the two flanges 4 and 6.

- 40 In the modification illustrated in Fig. 5 the individual pads 30, described with reference to the other figures, are replaced by a single cleaning pad 33, comprising several plies or layers of cotton fabric or gauze 45 (indicated at 31), said plies being sewed together to form one tubular member. Holding beads or projections, adapted for insertion between the holding flanges 4 and 6 of the cleaning device, are provided on the 50 inner surface of said tubular member at regular intervals, said beads being preferably produced by folding the various plies of the tubular member at fixed interspaces and maintaining them in folded condition 55 by means of seams (diagrammatically indicated at 32). The means for holding this pad in operative position, or for releasing the same, are the same as shown with respect to Fig. 1. In the operation of the device in connection with this modified pad 60 the beads are inserted between the flanges, which are then locked by means of the slide 11. After a portion of this pad has been

used the holding device may be released, and the pad may be turned so as to bring 65 successively another set of beads into registration with the holding flanges, whereupon the holding flanges can be closed again by the insertion of the slide 11.

It is obvious that the entire device after 70 removal of the pads or cushions may be sterilized in simple and efficacious manner, like any surgical instrument.

While only two specific forms of the invention are described in this specification, it 75 is understood that the same may be varied and modified without departing from the spirit of the invention and the scope of the appended claims.

I claim:

1. In a tooth cleaning device the combination of a metal back having a longitudinal slot, a flange projecting upwardly along the edge of the slot, a companion flange in opposition to said first named flange, a pad releasably inserted between said flanges, and means free of portions projecting into the space between said flanges for holding said pad in place.

2. In a tooth cleaning device the combination of a metal back provided with a longitudinal slot, a flange projecting upwardly from said back and rigidly connected therewith, another flange in opposition to said first named flange and oscillatably mounted 95 on said back, a pad removably inserted between said flanges, and a detachable means releasably connected with the back for forcing said movable flange in direction toward the stationary flange.

3. In a tooth cleaning device the combination of a metal back, a stationary holding element provided with gripping projections mounted on the back, another holding element movably mounted on the back in opposition to said first named flange and provided with gripping projections, a pad detachably inserted between said elements, means for forcing said movable element in direction toward said other element, and 105 means connected with said movable element for automatically moving the same in direction away from said other element when the first named means are released.

4. A tooth cleaning device, comprising in 115 combination with a back, a rigid holding flange projecting at an angle from the back, a movable holding flange projecting at an angle from the back, a third flange connected with said second flange and projecting below 120 the under surface of the back, means acting on said last named flange for forcing the second flange in direction toward the first named flange, and a pad removably inserted between said first two flanges.

EMANUEL LOEWENHERZ.
